DESCRIPTION

U.S. PATENT DOCUMENTS

FIG. 1 is a perspective view of a support for hanging/drying sports equipment in accordance with the present design;

1,137,900 A *	5/1915	Reichert	.....	211/163
3,310,180 A *	3/1967	Neagle	.....	211/205
3,827,571 A *	8/1974	Koutny	.....	211/59.1
D275,719 S *	10/1984	Ritchey	.....	D6/411
D300,289 S *	3/1989	Walter	.....	D6/411
D354,654 S *	1/1995	Mallen	.....	D6/552
D355,288 S *	2/1995	Mallen	.....	D32/58
D356,907 S *	4/1995	Jernigan	.....	D6/463
D387,216 S *	12/1997	Stone	.....	D6/405
D389,338 S *	1/1998	Vairo	.....	D6/458
5,862,924 A *	1/1999	Dumont	.....	211/85.7

FIG. 2 is a front elevational view of the support of FIG. 1;

FIG. 3 is a rear elevational view of the support of FIG. 1;

FIG. 4 is a right-side elevational view of the support of FIG. 1, the left-side elevational view being a mirror image thereof;

FIG. 5 is a top plan view of the support of FIG. 1; and,

FIG. 6 is a bottom plan view of the support of FIG. 1.

The broken lines showing structural supports and peripheral components in each figure are for illustrative purposes only and form no part of the claimed design.
